UNITED STATES PATENT OFFICE.

HALSEY W. TAYLOR, OF WARREN, OHIO.

DRINKING-FOUNTAIN.

1,286,835.

Specification of Letters Patent.

Patented Dec. 3, 1918.

Application filed March 25, 1918. Serial No. 224,410.

To all whom it may concern:

Be it known that I, HALSEY W. TAYLOR, citizen of the United States, residing at Warren, in the county of Trumbull and State 5 of Ohio, have invented certain new and useful Improvements in Drinking-Fountains, of which the following is a specification.

This invention consists of a drinking fountain embodying means adapted to deliver a stream of water in an arc with a mound of water of less width than height at its crest, thereby permitting drinking with facility and satisfaction while meeting every sanitary precaution. By delivering the 10 stream of water in an arc germs of disease cannot collect at the point of contact with the lips nor fall back upon the delivery nozzle, and the stream of water reforms beyond the drinking mound so that there is no objectionable spattering or spreading, thereby 15 permitting a glass or other receptacle to be easily filled at the point of descent of the curving column of water.

In the accompanying drawings, Figure 1 20 is a sectional view of one form of my invention looking toward the rear, and Fig. 2 is a top plan view thereof. Fig. 3 is a transverse section centrally through the device. Fig. 4 is a perspective view partly 25 broken away, of a modified form of the invention, showing a glass in receiving position for the discharging stream. Figs. 5 and 30 6 are enlarged detail views of the jet member shown in Fig. 4. Fig. 7 is a view in cross section of the drinking mound.

The invention in its broadest aspect comprises a water delivery connection, jet or nipple member 2 adapted to bring about the confluxion of a divided flow of water so that a 35 drinking mound of water will be built up, and maintained at the crest of an arc of a flowing body or stream of water at such relative distance from the point of discharge that water contaminated by the lips will not fall 40 back upon the discharge member. As shown herein, member 2 is provided with a plurality of outlets 3 and 4, respectively, which communicate with a common source of supply, said outlets moreover being inclined relatively to each other in a vertical plane, whereby two jets of water are ejected into confluxion and projected as a single column inclined to the vertical, and further, whereby 45 the column of water is caused to be more or less flattened and distended on curved lines to provide a distinctive mound at the crest of

the arc of flowing water. Outlet 3 directs one jet of water more or less perpendicularly, whereas outlet 4 directs another stream of water at an inclination into the first jet, the 50 effect being that the confluent waters are projected to one side of the connection and with the further peculiar result that the stream of water is flattened in two planes, first in an inclined plane, and second in a 55 vertical plane. In this way a column of water is projected upwardly to form a drinking mound beyond the point of confluence and at the crest of the curve or where the column reaches its highest altitude. The 60 mound thus built up is narrow enough to pass into one side of the mouth and also deep enough to give a large draft and while there is a momentary retardation of the elevated water contributing decidedly to the 65 taking in of a large draft at once there is no retention of germs or organisms to endanger the next person drinking from the same column because such organisms are flushed away immediately.

It is also desirable in a device of this kind to prevent contact of the lips with the metal connection or nipple 2; therefore, I mount a skeleton member 5 as a guard above the nipple, the legs of said member being fastened 70 in any suitable way to the rim 6 of the oval basin 7 which supports nipple 2 upon the raised seat 8 at one end thereof, see Fig. 1. Nipple 2 has a screw-threaded extension projecting through an opening in said seat, and 75 a nut 9 secures the nipple and a sealing washer 10 in place, while an elbow member 11 screwed to the nipple extension beneath nut 9 supports a controlling valve 12 and a supply pipe 13 extending to the rear of the 80 basin.

Basin 7 is preferably elongated in the line of discharge, and the descending water is carried away through the perforated strainer plate 14 and a sewer pipe connection 15. An 85 integral arm 16 at the rear of the basin serves to secure the basin upon a wall or other upright, but any suitable means may be used to hold the basin and nipple at the proper elevation for drinking, and if desired, the basin may be omitted and another means of support provided for the nipple, without departing from the more essential features involved in the invention.

In Figs. 4 to 6, inclusive, I show a modified 90 form of the invention in which the same principles of delivery and the same ad-

vantageous results are obtained, but with additional sanitary safe-guards. Thus, a jet or nipple 17 is therein shown which embodies two short tubes 18 and 19 of different diameter through which the water flows in different volume and different velocities to produce a single inclined curved stream with a distinctively raised drinking crest. Each tube has an outwardly and downwardly curved edge 20 at its outlet end to guard against the drawing up by capillary action of any contaminated water that may find a lodging upon the nipple member at the base of the tubes; and the tubes are also protected from contaminating touch by a guard 21 spanning both tubes and having a pair of openings 22 through which the separate streams of water pass before coming together at the desired angle for common delivery and with the result and effect as described.

What I claim is:

1. In a drinking fountain, means directing distinct jets of water in confluence at an inclination to the perpendicular to produce a curving column of water with a drinking mound of less width than height at its crest.
2. A water-delivery connection for use in drinking fountains, comprising a nipple member having a plurality of jet outlets inclined relatively to each other and producing a confluent curving discharge at one side of said member.
3. A water-delivery connection for use in drinking fountains, comprising a nipple member having a plurality of jet outlets inclined toward each other and promoting conflúxion of the jets and a widening of the stream in a vertical plane and at the crest of an arcing discharge at one side of said member.
4. A nipple member for drinking fountains having a vertically-disposed jet outlet and an inclined jet outlet of smaller size at one side thereof adapted to jet a smaller stream of water into confluence with the vertical stream, the axes of said outlets being on intersecting lines, and means to connect said member with a source of water supply under pressure.
5. In a drinking fountain, a basin having a water delivery connection provided with a plurality of jet openings in inclined relation and arranged to direct a confluent discharge of water in a single curving stream into said basin and with a distinctive drinking mound at the crest of said stream.
6. In a drinking fountain, a basin having a nipple member at one side thereof provided with vertical and inclined jet open-

ings arranged to direct distinct jets of water into confluence in an arc at one side of said member, a valved supply pipe connected with said member, and a guard in covering relation to said nipple member.

7. A basin having a drain opening in its bottom, a support for said basin, a nipple member mounted within said basin having a plurality of jet openings disposed in angular relation to discharge a curving column of water at a predetermined altitude above and into said basin, and a guard for said nipple member.

8. A basin having an integral arm at one side and a raised seat therein, a nipple member upon said seat having a screw extension, a nut for said extension securing said member in place, a skeleton guard projecting over said nipple member having legs detachably secured to said basin, and a valved supply connection engaged with said extension.

9. A nipple member for a drinking fountain having a pair of discharge jets inclined relatively to each other to bring separated jets of water into confluence, and a guard spanning said jets having openings for the passage of the water.

10. A method of producing a drinking mound in a curving stream of water, consisting in forming the stream into substantially flat spreading bodies of water successively, first in an inclined plane, and secondly, in a plane at right angles to the first plane.

11. A method of producing a raised drinking mound in a curving stream, consisting in flattening the stream in one plane and then reforming the stream into a drinking mound in a vertical plane at the crest of the curving stream.

12. A method of producing an arched drinking mound of flowing water, consisting in projecting a body of water upwardly in an inclined plane while distending the body of water transversely, then drawing the distended water together again, and then distending it in a vertical plane at the crest of the curving stream.

13. A method of producing a sanitary drinking mound, consisting in delivering a stream of water upwardly, and in directing a second stream of water into the first stream and projecting the confluent waters laterally in a single arching stream with a raised drinking mound at its crest.

Signed at Warren, in the county of Trumbull and State of Ohio, this 21st day of March, 1918.

HALSEY W. TAYLOR.
